LAMP

Gerald Moss, San Francisco, Calif.

Application June 19, 1957, Serial No. 46,651

Term of patent 14 years

(Cl. D48—20)

Fig. 1 is a side elevational view of the lamp showing my new design.

Fig. 2 is a horizontal section on line 2—2 of Fig. 1.

Fig. 3 is a horizontal section on line 3—3 of Fig. 1.

Fig. 4 is an elevational view as seen from the right of Fig. 1 but with the lantern element and hook omitted for convenience of illustration.

Fig. 5 is an elevational view taken from the side opposite that shown in Fig. 4.

The side of the lamp not shown is the same as that shown in Fig. 1 and the lantern member is cylindrical and symmetrical.

I claim:

The ornamental design for a lamp, as shown and described.
